UNITED STATES PATENT OFFICE

HENRY STEEN, OF VASHON, WASHINGTON

NEWSPAPER RECEPTACLE

Application filed August 14, 1929. Serial No. 385,887.

This invention relates to improvements in devices designed to take deliveries of newspapers or the like, and in particular on rural routes where such articles, delivered under usual conditions, are subjected to the injurious effects of the weather.

Its objects, generally stated, are, to provide a suitable container having an automatic closure therefor, said container being 10 tiltably connected with supporting means and so balanced that when empty it will stay in a horizontal and open position, and when the article to be delivered is placed in the container, the weight of said article causes it to 15 assume a vertical and closed position, thereby rendering the container weather-proof; to afford a device, which, by virtue of the positions it is adapted to assume, will serve as a signal to indicate whether or not a delivery has been made to it; and, to make available a device of this character which is simple in construction, notwithstanding its automatic features.

Other objects, advantages and capabilities 20 will appear as the description of the invention progresses.

In the accompanying drawings—

Figure 1 is a side elevation of the device 25 complete and in open position, a post on which it is mounted being broken away.

Fig. 2 is a side elevation of the same in closed position, the container being broken away to indicate the water-tight construction of one end thereof and also to show a newspaper deposited in the container.

Fig. 3 is a cross section drawn along the line 3—3, of Fig. 1.

Referring more particularly to the drawings, 1 denotes a container designed to have a 30 diameter sufficiently large to receive a newspaper of any size when it is folded in the usual manner for delivery, and to be of a length somewhat longer than the folded newspaper. In the present embodiment of the 35 invention this container is shown as cylindrical, but obviously it may be rectangular or in any other suitable form. The closed end 2 of the container has a smooth upper surface and is joined to the body of the container, as 40 at 3, to permit it to shed water. The other

end of the container is provided with a rim, generally designated as 4, which is formed by turning the free end of said body over an annular section of wire 5. A closure 6 for the container, in form complementary to the 55 open end of the container and having an apertured arm 7, is hingedly connected with said wire. This hinged connection may be established by forming ears integral with the body of the closure and bending them around exposed sections of said wire in the rim, as 60 indicated at 8.

A bracket, generally designated as 10, is 65 fixedly secured to the container, and extends longitudinally thereof slightly more toward the forward or receiving end of the container rather than the closed end, to preserve a balance for the container and other parts of the device which will presently be described with more particularity. The bracket is preferably bent from a piece of sheet metallic stock, and is provided with a seat 11 for the container, through which the bracket may be secured to the container by the rivets 12, and a pair of depending portions 13 disposed in 70 spaced parallel relation, each having an opening 14 oppositely disposed.

Said portions are adapted to straddle one 75 end of a support, the support having a flat body portion 20 and a pair of spaced and parallel side portions 21. The support is also provided at said end with an integral depending and apertured ear 22 located adjacent to and parallel with one of the side portions 21, and a pin 23, as shown, secured 80 in the portions 21 and extending through the openings 14 in said bracket, said pin affording a pivotal connection for the bracket with the support. 24 denotes a link pivotally connected with the arm 7 of the closure and also 85 pivotally connected with the ear 22. Said support is designed to surmount and be secured to a post 30 which will serve to elevate the device to a height that will be convenient 90 for the use in which the device is employed. 95

Having in view the respective weights of the container, the closure and the parts connecting the closure with said support, the bracket preferably is disposed relative to the container and mounted on the support about 100

as indicated in Fig. 1, to the end that the container will, when empty, maintain a horizontal position with the closure opened, as shown.

5 In making a delivery to the device, as for instance, the newspaper heretofore referred to, the same is inserted within the container so that it is entirely within the open end thereof. The weight of the newspaper will 10 cause the container to tilt forwardly, and as said movement of the container progresses, the link 24 operating on the arm 7 serves to bring the closure up toward the open end of the container, and when the container has 15 dropped to the vertical position shown in Fig. 2 the container is completely closed, the newspaper 31 then occupying the position as shown. The container as now located will protect the newspaper from the weather and 20 inform the recipient that the newspaper has been delivered. In taking the newspaper from the container, said container is returned to a horizontal position by hand, when the link, operating in a reverse manner on said 25 arm, will cause the closure to assume the open position indicated in Fig. 1, and on removal of said newspaper the device is again in receiving position.

While it is practical and ordinarily desirable to use the weight of the delivered article in closing the container and making the same serve as a signal, the device can be conveniently operated when a delivery is made by throwing the container into a vertical position manually after the newspaper has been placed therein, the hand of the user then being in a position so that the container can be thus manipulated handily. If accumulations of snow and ice should render this last 40 named mode of operation desirable, the movable parts will cooperate in a most positive manner.

This device is primarily intended to be used in the ways and for the purposes particularly described, but it is evident that it is adapted to receive deliveries of other suitable articles, and that its elements will also function as a mail box.

Changes in and modifications of the construction described may be made without departing from the spirit of my invention or sacrificing its advantages, hence it is desired that I be not confined to the specific structure set forth, except as limited by the appended 55 claims.

I claim:

1. A newspaper receptacle, comprising a container closed at one end and open at the other end, a closure hingedly connected with the open end of the container, a bracket extending from the container, a support adapted to seat the container normally in a horizontal and receiving position, a pivotal connection for the bracket with the support and 65 whereby the container may be tilted to an ap-

proximately vertical position with its open end disposed downwardly to signal that a newspaper has been deposited in the container, and a link pivotally connected with the closure and the support adapted to shut the closure simultaneously with the tilting of the container. 70

2. In a device of the class described, a container having a closed end and an open end, a closure swingingly connected with said open end, means for maintaining the container in an approximately horizontal position, means whereby the container may be tilted into an approximately vertical position by the weight of an article inserted within the container, and means whereby when the container is tilted vertically said closure will be automatically shut and when the container is disposed horizontally said closure will be automatically opened. 75

3. In a device of the class described, a container having a closed end and an open end, a closure hingedly connected with said open end, means for seating the container horizontally to bring the container into normal receiving position, means for tilting the container vertically to signal that an article has been deposited in the container, and automatic means for progressively bringing the closure into closed position as the container is tilted vertically and for progressively bringing the closure into open position as the container is seated horizontally. 80

4. In a newspaper receptacle, an elongated container having a closed end and an open end, a closure associated with said open end, a support, a connection for the container with the support of such a character that when the container is empty it will be disposed in a lowered position and when a newspaper is deposited therein the weight of the newspaper will cause it to assume a raised position, and automatic means for progressively bringing the closure into closed position as the container is raised and for progressively bringing the closure into open position as the container is lowered. 100

5. In a newspaper receptacle, an elongated container, a support, and a tiltable connection for the container with the support of such a character that when the container is empty it will be balanced in a lowered position and when a newspaper is deposited therein the weight of the newspaper will cause it to be unbalanced and assume a raised position. 105

HENRY STEEN.
